ATTORNEY

UNITED STATES PATENT OFFICE

HARRY P. ECKSTEIN, OF WEEHAWKEN, NEW JERSEY

GARMENT

Application filed June 18, 1926. Serial No. 116,798.

This invention relates to undergarments, and more particularly to sanitary undergarments.

The invention has as one of its objects the provision of a highly sanitary undergarment of the so-called "bloomer" type, and an important feature of the invention is that the garment is formed partly of a material of one characteristic, and partly of a material of a different characteristic, which is sewn into the undergarment without adhering to the outer material. For example, the first named material may be of any suitable material, while the second named material may be rubber or any desired product of latex, having the characteristic of resisting the chemical action of menstrual flow or other bodily excreta, of being stainless, and being washable.

Still another object of the invention relates to the provision of an undergarment in which a material having special characteristics is positioned to obstruct the body effluvia, and thereby protect the fabric therefrom, thus insuring a relatively long useful life to the garment. On account of the highly deleterious chemical action of menstrual flow upon ordinary sheer fabric, the protection effected by the special construction of the undergarment of the present invention greatly extends the useful life.

A further object of the invention is to provide for ready and convenient washing of the undergarment, thereby to preserve the cleanliness thereof and to increase the personal comfort and convenience of the wearer.

The undergarment of the present invention furthermore retains the trim, snug lines and silhouette of a single sheer garment of present day styles.

The undergarment of the present invention further eliminates the necessity of wearing additional undergarments of required protection during the menstrual flow.

Other objects will appear from the following description taken in connection with the accompanying drawings in which

Figure 1 is a front elevation of one embodiment of the invention;

Figure 2 is a rear elevation thereof;

Figure 3 is a detailed view of the specially characterized portion of the garment;

Figure 4 is a corresponding view of so much of the main portion of the garment as is covered by the portion of Figure 3 when assembled in the complete garment; 55

Figure 5 is a section taken on the line 5—5 of Figure 2 and Fig. 6 is an enlarged detail view of a portion thereof.

Like reference characters refer to like 60 parts in the several figures of the drawing.

In the following description and claims, parts will be identified by specific names for convenience of expression, but they are intended to be as generic in their application to similar parts or equivalent construction as the art will permit. 65

Referring now to Figures 1 and 2; it will be seen that I have shown for the purpose of illustrating the invention, an undergarment 70 for ladies, popularly designated "bloomers." Many of the details of such bloomers, such as their shape, the arrangement of the waist line, the length of the leg, etc., may vary from time to time, in accordance with dictates of 75 convention or fashion. Also, since the invention may be applied to any form of undergarment for children, as well as for women, it is not thought necessary, in the present state of the art, to describe herein with particularity, the construction of such portions as have 80 been mentioned.

It is understood, however, that the undergarment consists of a body portion 10 having an anterior side 11, (see Figure 1) and a posterior side 12 (see Figure 2), with depending bifurcations 13, 13, forming a usual crotch therebetween. Any material suitable for undergarments may be used. The material is sewn into the form illustrated, i. e., 85 to fit the human form.

An additional element 20 comprising an insert or overlay, and formed of a differently characterized material, is cut to a symmetrical quadrilateral shape, such as illustrated in 90 Figure 3. It is understood that the element 20 has its greatest longitudinal dimension considerably greater than its greatest transverse dimension, when positioned in the completed undergarment as seen in Figures 1 and 100

2. The greatest longitudinal dimension is on the longitudinal center line of the garment, and the maximum transverse dimension is near one end of the element, thus forming a relatively long posterior wing 21, and a short anterior wing 22. Although the element 20 is shown with straight line edges, any equivalent arrangement may be employed, without departure from the spirit and scope of the invention.

10 The element 20 is attached within the trunk of the undergarment, on the inner surface of the crotch, with the longitudinal axis coincident with the longitudinal center line of the garment. It is positioned so that the portion of maximum transverse width is at the bottom of the crotch. Thus the anterior, short wing 22 extends upward in front of the wearer only to a limited extent, and interferes in no way with the activities of normal life. This sanitary inset is so shaped that it tends to eliminate all unnecessary protective material, decreasing the heating possibilities of other so-called sanitary undergarments.

15 25 The posterior, long wing 21 of the element 20 extends upwardly a considerable distance in the rear, thus giving ample protection in substantially every posture assumed by the wearer.

30 The element 20 is preferably secured to the inner surface of the remainder of the undergarment by having its edges sewn to a tuck 30 taken in the fabric of the garment. When so secured, the tuck 30 forms in outline a quadrilateral 31 (see Figure 4) which conforms to the shape of the element 20 except that the maximum transverse dimension of the quadrilateral 31 is relatively greater than the maximum transverse dimension of the element 20, while the maximum longitudinal dimensions are substantially equal. The edge of the element is placed in juxtaposition to the fold of the tuck 30, as illustrated in detail in Figure 5, and stitches 32 are taken 35 40 45 around and through the doubled fabric and the rubber.

50 The portion of the material within the tuck 30, designated 33, is thus relieved of transverse strain, and the useful life of the undergarment is thus greatly extended.

55 Thus it will be seen that a garment of great usefulness and desirability is provided. The element 20 can readily be washed off and the garment worn almost immediately. An important feature with present day styles is that there is only a single thickness of material at the waist line or on the limbs, and thus the modish slimness at present in vogue is preserved by this improved garment. Furthermore the gusset protects the external garment as well as the undergarment and permits external garments of any desired material to be worn at any time.

60 The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claim.

70 75 80 85 90 95 100 105 110 115 120 125 130

What is claimed is:

The combination with a lady's undergarment of a protective gusset of substantially moistureproof material adapted to cover a portion thereof, said gusset being positioned at the crotch of said garment and being secured to the cloth material of said garment only at the edges of the gusset, the intermediate portion being loose from the contiguous cloth material and concealed from view thereby, and being less in extent than the underlying cloth material, whereby said cloth material is adapted to rest in natural folds said gusset being adapted to protect the various garments from body effluence.

Signed at New York, in the county of New York and State of New York this 17th day of June, A. D. 1926.

HARRY P. ECKSTEIN.
